Primary Examiner — Marianne Pandozzi*(74) Attorney, Agent, or Firm* — McAndrews, Held & Malloy, Ltd.**(57) CLAIM**

We claim an ornamental design for a pickle pipe, as shown and described.

DESCRIPTION

FIG. 1 is an environmental top perspective view of a pickle pipe showing our new design;

FIG. 2 is a top perspective view thereof;

FIG. 3 is a bottom perspective view thereof;

FIG. 4 is a side view thereof;

FIG. 5 is another side view thereof;

FIG. 6 is a top plan view thereof; and,

FIG. 7 is a bottom plan view thereof.

The dashed broken lines in FIG. 1 depict environment subject matter that forms no part of the claimed design. The dashed broken lines in FIGS. 3 and 7 depict portions of the pickle pipe that form no part of the claimed design.
